UNITED STATES PATENT OFFICE.

HUBERT OSWALD BEDGOOD, OF GLASGOW, SCOTLAND, ASSIGNOR TO LOBNITZ & COMPANY LIMITED, OF RENFREW, SCOTLAND.

DRAG-LINE EXCAVATOR.

Application filed May 9, 1924. Serial No. 711,950.

To all whom it may concern:

Be it known that I, HUBERT OSWALD BEDGOOD, of Glasgow, Scotland, a subject of the King of Great Britain, have invented 5 certain new and useful Improvements in Drag-Line Excavators, of which the following is a specification:

This invention relates to what are known as "drag-line" excavators. In such excavators, as at present in use, the bucket is suspended, usually, from the jib or boom by means of a hoisting rope which first passes over a pulley at the end of the boom, then down and round a pulley connected 10 with the bucket, then up and over a second pulley on the boom, and, finally, down again to the pulley block of the bucket to which it is secured. With this arrangement not only are two pulleys required at the end 15 of the boom but the rope suspension is three ply.

When the bucket is dropped the heavy pulley block at the lower end of the tackle frequently strikes the bucket with the result 20 that bucket, block, and rope are damaged. The pulleys being fixed in position on the boom restrict and limit the freedom of movement of the hoisting rope.

The object of the present invention is to 25 provide an arrangement which shall obviate the disadvantages of the present construction by the substitution therefor of a single, pivotally suspended pulley at the end of the boom and a duplex or parallel 30 hoisting rope which passes over said pulley and is secured to a comparatively small pulley block for the tipping rope and which is connected with the bucket.

In order that the invention may be properly 35 understood we will now describe, by way of example, one mode of carrying the invention into practice, reference being made to the annexed drawings, whereon:—

Fig. 1 is a side elevation of the drag-line 40 excavator.

Fig. 1^a is a detail view of part of Fig. 1.

Fig. 2 is a plan, with certain parts removed, of the excavator shown in Fig. 1.

Fig. 3 is a side sectional elevation to an 45 enlarged scale of the end of the boom, with its accessory parts, the section being taken on line 3—3, Fig. 4.

Fig. 4 is an end elevation, partly in sec-

tion on line 4—4, Fig. 3, but with certain parts removed, and 55

Fig. 5 is an end elevation partly in section of certain parts shown in Fig. 3.

The excavator is carried by a usual arrangement such as bogies 1 upon which are mounted a base 2 carrying a revolving table 60 or platform 3 which latter has mounted upon it a derrick 4 and also carries the boiler, winches and other mechanism necessary for the operation of the excavator.

Pivoted to the front of the revolving table 65 or platform 3 is a boom or jib 5 which is operated by means of a derrick rope 6 passing over a multiple block 7, near the forward end of the boom, and a block 8 near the top of the derrick 4. The rope 6

is led over a jockey pulley 9 upon the derrick and thence to the derrick drum 10. The drag-rope 11 is connected by a chain 12 and tipping rope 13 to the pulley 13^a 70

and bucket 14 and passes through a fair 75 lead with guide pulleys 15, 16, to a drag-drum 17. The drag-drum 17 and the hoisting drum 20 are geared together and are driven from a single engine which also drives the drum 10. All the foregoing parts

are substantially the same as in the usual construction of drag-line excavator and 80 form no part of the present invention.

In accordance with this invention the bucket 14 is provided with a parallel hoisting rope 21 (see also Fig. 1^a) which passes round the half block 13^b secured to the pulley block 13^a, over a duplex pulley 22 carried on the end of the boom, and thence to the hoisting drum 20. The bucket chain 14^a is attached directly to the pulley block 85

13^a. The tipping rope 13 works over the pulley in the block 13^a.

On referring to Figs. 3, 4 and 5, it will 90 be seen the pulley 22 is mounted on a pin 23 in the block 24 which has three arms 24^a, 24^b, and 24^c, the block being made up of two side plates joined together. A riveted

pin 25, provided with a roller, connects the two arms 24^c and prevents the duplex rope 21 leaving the pulley. The block 24 is connected to the boom 5 by a connection comprising a block 26 pivoted, by means of a pin 27, to lugs 28 depending from the boom, the block having projecting trunnions 29

upon which are pivoted the arms 24^a of the 95

100

105

block 24. In this way the block 24 is free to swing both longitudinally and laterally of the boom so that it can readily accommodate itself to a change in position of the bucket relatively to the boom.

In order to make the suspension of the hoisting pulley more stable, without detracting from its freedom of movement, it is also connected to the boom by its arms 10 24^b which are pivotally jointed by pins 32, 34, to a shackle 31 secured to the fixed eye 30 at the end of the boom. The shackle 31 is pivoted at its lower ends, by means of the pin 32 to a block 33 (see Fig. 5) provided with a pin or trunnions 34 journalled in bearings in the arms 24^b. The ends of the trunnions 34 are reduced and screwed at 35 and are provided with washers 36, nuts 37 and split pins 38.

20 It is obvious the pivotal joint permits the pulley to swing laterally of the boom, while, when the pulley swings longitudinally about 29 the shackle 31 can work freely in the eye 30.

25 It will be seen the pulley 22 is so flexibly carried by the pivotal joints that whilst it can accommodate itself to all movements of the bucket 14 it is prevented twisting or spinning about its connection to the boom 30 with the result that the duplex hoisting rope is not liable to twist during the raising or lowering of the bucket.

The drag-rope 11 and bucket are operated as usual.

35 The whole arrangement provides a simplified and flexible gear capable of being operated more rapidly than with the usual type of excavator.

Having now fully described my invention 40 what I claim and desire to secure by Letters Patent is:—

1. The combination with the boom of a drag-line excavator of a single pulley over which the bucket hoisting rope is adapted to pass, the pulley being pivotally connected to the boom at two places whereby the pulley can swing both laterally and longitudinally of the boom.

50 2. The combination with a boom of a drag-line excavator of a single duplex pulley over which the bucket hoisting rope is adapted to pass and connections between the boom and the pulley whereby the latter is

free to move laterally and longitudinally of the boom while being maintained against 55 twisting.

3. The combination with the boom of a drag-line excavator of a single pulley over which the hoisting rope is adapted to pass, a pulley block for the pulley, and a connection between the boom and the pulley block comprising lugs on the boom, and a block pivoted to said lugs and to said pulley block, the axes of the two pivots being at 60 right angles to one another.

4. The combination with the boom of a drag line excavator of a single pulley over which the bucket hoisting rope is adapted to pass, and inflexible means connecting said pulley to said boom, said means comprising 70 a pulley block for the pulley, arms on the pulley block, lugs on the boom, and a block pivoted to said arms and to said lugs, the axes of the pivots being at right angles to one another.

5. The combination with the boom of a drag-line excavator of a single pulley over which the hoisting rope is adapted to pass, a pulley block for the pulley, a connection between the boom and the pulley block comprising lugs on the boom and a block pivoted to said lugs and to said pulley block, the axes of the two pivots being at right angles to one another, and a second connection between the boom and the pulley block 80 comprising a fixed eye on the boom, a shackle passing through said eye, a block fulcrumed to said shackle and also to said pulley block, the axes of the two fulcrums being at right angles to one another.

6. A drag-line excavator comprising a movable structure, a boom thereon, a bucket, a bucket hoisting rope, and a pulley on the boom over which said bucket hoisting rope passes to the bucket, said pulley being jointed to the boom at two places, the planes of the pulley in all positions thereof intersecting in a common axis extending along the boom.

In testimony whereof I affix my signature 100 in presence of two witnesses.

HUBERT OSWALD BEDGOOD.
